UNITED STATES PATENT OFFICE

163,946

FLOATING MINNOW CONTAINER OR SIMILAR ARTICLE

Kenneth E. Greene, Chicago, Ill., assignor of one-fourth to Lawrence T. Barnett and Sherman R. Barnett, Chicago, Ill.

Application May 27, 1950, Serial No. 10,239

Term of patent 7 years

(Cl. D31—4)

To all whom it may concern:

Be it known that I, Kenneth E. Greene, a citizen of the United States, residing in the city of Chicago, State of Illinois, have invented a new, original, and ornamental Design for a Floating Minnow Container or Similar Article, of which the following is a specification, reference being had to the accompanying drawing, forming a part hereof.

Fig. 1 is a perspective view of a floating minnow container showing my new design.

Fig. 2 is a side elevational view thereof.

Fig. 3 is a top plan view thereof.

I claim:

The ornamental design for a floating minnow container or similar article, substantially as shown.

KENNETH E. GREENE.
